H. T. HETTINGER

CLOTHES HANGER

Filed April 10, 1925

UNITED STATES PATENT OFFICE.

HENRY T. HETTINGER, OF PITTSBURGH, PENNSYLVANIA.

CLOTHES HANGER.

Application filed April 10, 1925. Serial No. 22,221.

To all whom it may concern:

Be it known that I, HENRY T. HETTINGER, a citizen of the United States, and a resident of Pittsburgh, in the county of Allegheny and State of Pennsylvania, have invented a new and useful Improvement in Clothes Hangers, of which the following is a specification.

This invention relates to a combined coat and trouser hanger, and has for its primary object the provision of a foldable hanger which may be compactly folded into a small space with ease, and readily unfolded whenever desired for use as a hanger, as well as the provision of a sturdy, neat and convenient hanger of this character which can be economically manufactured.

It is also an object to provide a foldable suit hanger in which the extensible slides adapted to project from the main cross bar are firmly supported while in extended position, and are so fashioned and coordinated with the cross bar as to be automatically locked in folded condition by the mere sliding thereof towards the cross bar, the locking means serving the dual function of positively securing the slides against bodily separation from the cross bar upon withdrawal to extended or operative position and the resilient locking of the same in place when moved to its folded or inoperative position.

A further object is to provide a hanger of the character referred to in which the portions for suspending the trousers may be readily detached from or fastened to the cross bar so that the coat supporting and trouser supporting portions may be used independently, or readily disconnected for packing, if desired.

These and other objects of the invention will more fully appear when taken in conjunction with the following description and the appended claims.

In the drawings forming a part of the application, Fig. 1 is a perspective view showing the entire hanger in its unfolded condition ready for use, and illustrating the method of suspending the trouser supporting portion from the main cross bar; Fig. 2 a similar view of the main cross bar and the slides which cooperate therewith, the slides being shown in their folded or inoperative position with the offset bent portions forming the spring latch engaged with the locking apertures of the cross bar; and

Fig. 3 a similar view of the portions which form the trouser support, illustrating the relative positions which the parts assume when the trouser supporting portion is detached and adjusted for packing.

In the drawings the main cross bar is indicated generally by the reference numeral 1, and comprises a top wall 2, substantially parallel depending side flanges 3, 3', and the depending end flanges 4, 4', the end flanges joining the side flanges and cooperating to provide a recess at the bottom face of the cross bar.

The top wall 2 is equipped at a point intermediate the ends of the cross bar with a latch receiving opening 5, preferably of cruciform shape, while each of the depending side flanges is provided with an elongated catch-receiving opening or aperture 6, 6', such as shown at 6 and 6', these openings being located, in the preferred form of the invention, adjacent the end flanges. Each of the end flanges is provided with a pair of spaced-apart slightly elongated guiding apertures 7, 7', which are adapted to have threaded therethrough the two limbs 8, 8' of the extensible slides, the outer extremity of the slide being closed as clearly shown in the drawings, while the inner extremities thereof are left free and project within the recess formed at the under or bottom face of the cross bar. The inner extremity of one of the limbs, limb 8 as shown in Fig. 1, is slightly offset in the manner indicated at 9 to provide a spring catch, which is adapted to resiliently but locking engage with the opening 6 when the slide is moved to its folded or inoperative position, in the manner indicated in Fig. 2.

The slides are preferably formed of resilient wire bent upon itself to the desired shape, thus providing a comparatively strong construction which is of light weight. A slide similar to that just described in detail is provided at each end of the cross bar, one being threaded through the spaced guiding apertures of the depending flange 4 and the remaining one in a similar manner through spaced guiding apertures in the end flange 4'. Both slides are identical in construction.

The offset portions 9 of the slides perform a dual function. Besides serving as a spring catch to lock the slides against relative movement with respect to the cross bar when moved to their inoperative or folded

2
positions, as shown in Fig. 2, these offset portions 9 also serve as limiting stops or abutments for determining the outward travel of the slides when withdrawn to their 5 operative or coat-supporting position. Upon withdrawal, the movement of the slide is arrested by the abutting of the offset portion 9 with the depending end flange through which it is threaded. The cooperation 10 between the parts, nevertheless, lend themselves to ready assembly.

The portion of the hanger constituting the trouser support, comprises the bent loop indicated generally by the reference numeral 15 10 and includes the pair of substantially parallel depending limbs 11, 11', closed at their upper end, and having their lower free ends pivotally connected to a pair of clamping strips 12, 12', the pivotal connection of 20 the limb 11 with the strip 12 being clearly indicated at 13 in Figs. 1 and 3. The strips 12 and 12' may be constructed of any suitable material, but are preferably made of channel shaped metal sections, the channels 25 of which are fitted with strips of fabric, such as felt, in the manner clearly indicated at 14, 14', these fabric strips forming suitable surfaces for engaging the garment in a fashion which will be clearly understood 30 by those familiar with this art. A portion of the inwardly extending top flange forming the channel of each of the clamping strips 12 and 12' is cut away, and the remaining portion bent outwardly to form the 35 notched flanges 15, 15', the notches being adapted to receive the lower extremities of the limbs 11 and 11' when the clamping strips are swung about their pivotal connections 13 so as to occupy a position substantially at right angles to the body of the loop 10. The manner in which the depending limbs of the loop engage these notches is 40 clearly illustrated in Fig. 1, while Fig. 3 shows the limbs disengaged from the notches 45 with the loop 10 swung so as to lie in substantially longitudinal alignment with the strips for the purpose of causing the several parts to occupy less space thus enabling 50 them to be more readily packed for transportation.

Pivots attached to the closed end of the loop 10 is a bent wire catch 16 the intermediate portion of which is in the form of an eyelet encircling the loop and having 55 the extremities 17, 17' projecting laterally therefrom. In order to permit the strips 12, 12' to be readily separated or forced towards each other into gripping relation with the garment at will, a bent wire slide 18 of well 60 known construction is provided, having the eyelets at its opposite ends threaded upon the respective limbs of the loop.

In use, whenever it is desired to suspend 65 the trouser supporting portion from the cross bar, the latch 16 is swung around its

pivot so that the extremities 17, 17' lie in a vertical plane, enabling the latch to be projected upwardly through the receiving opening 5, with the latch above the top wall 2. After being projected through the opening 70 in this manner, the latch is then swung so as to position the extremities 17, 17' in a horizontal plane with the extremities resting upon and supported by the top wall 2, all in a manner clearly shown in Fig. 1. 75

With the trouser supporting means attached to the cross bar, the pair of slides mounted therein may be withdrawn from the recess to freely extended position, as 80 shown in Fig. 1, when the hanger is ready for use for supporting both the coat and the trousers of a suit, or for supporting other garments in an obvious way.

In order to readily suspend the entire hanger from a hook or similar support, a 85 supporting loop such as shown at 19 is provided, the lower laterally bent extremities of which are adapted to be projected downwardly through the opening 5, so as to contact with the bottom face of the top wall 2. 90 When attached in this manner, the lower extremities of the loop lie within the offset portions of the opening 5 so as to hold it against rotation relatively to the cross bar. The provision of two pairs of oppositely disposed offsets in the opening 5 enables the body of the supporting loop to be positioned either parallel with or transversely of the 95 axis of the cross bar.

In order to pack the hanger into a 100 comparatively small compass for transportation or for storage, the trouser supporting means can be readily detached from the cross bar by releasing the latch 16. Thus removed, the parts thereof may be brought to the relative positions shown in Fig. 3, and the coat supporting portions moved to that shown in Fig. 2. It is obvious that with the trouser and coat supporting means detached from each other, and in their folded condition, the 105 entire hanger will occupy but very little room.

It is thus seen that the invention provides a suit hanger which is extremely neat in appearance, of simple and sturdy construction, 110 which may be manufactured at a nominal cost, one in which the several parts may be quickly and easily assembled and locked in the desired positions, and one in which the slides mounted in the main cross bar are 115 fashioned so as to form a firm support when moved to extended condition while at the same time providing a convenient means for both locking them in their folded condition as well as limiting the extent to which 120 they may be withdrawn when desired for use. 125

I claim:

1. A foldable suit hanger comprising a 130 cross bar having a body provided with a

- recess in its bottom face and depending flanges bordering said recess, said flanges being provided with apertures extending therethrough, a pair of oppositely disposed 5 resilient slides slidably mounted in the cross bar, the inner ends of the slides projecting within the said recess and having offset portions adapted to lockingly engage with said apertures for resiliently holding the 10 slides against movement relatively to the cross bar.
2. A foldable suit hanger comprising a cross bar having a body provided with a recess in its bottom face and depending side 15 and end flanges bordering said recess, the said side flanges being equipped with catch-receiving openings, a resilient bent wire slide slidably threaded through each of the end flanges with its inner extremity projecting 20 into the said recess, the said inner extremity being equipped with an offset portion forming a spring catch, said offset portion being adapted to engage with one of the openings in said side flanges to hold the slide against 25 movement relatively to the cross bar.
3. A foldable suit hanger comprising a cross bar having a body provided with a recess in its bottom face and depending side and end flanges bordering said recess, the 30 said side flanges being equipped with catch-receiving openings, and the end flanges with a pair of spaced guiding apertures, a U-shaped slide slidably mounted at each end of said cross bar, the limbs of said slide projecting through the said guiding apertures 35 into the said recess, one of said limbs being bent to form an offset portion serving as a spring catch adapted to engage one of the 40 openings in the side flanges of the cross bar for holding the slide in folded position and to abut the end flange to limit the outward travel of the slide when drawn to extended operative position.
4. A foldable suit hanger comprising a cross bar having a body provided with a recess in its bottom face and depending flanges bordering said recess, said flanges being provided with apertures extending therethrough, a pair of oppositely disposed 45 resilient slides slidably mounted in the cross bar, the inner ends of the slides projecting within the said recess and having offset portions adapted to lockingly engage with said 50 apertures for resiliently holding the slides against movement relatively to the cross bar,
5. A foldable suit hanger comprising a cross bar having a body provided with a recess in its bottom face and depending flanges bordering said recess, said flanges being provided with apertures extending therethrough, a pair of oppositely disposed 55 resilient slides slidably mounted in the cross bar, the inner ends of the slides projecting within the said recess and having offset portions adapted to lockingly engage with said 60 apertures for resiliently holding the slides against movement relatively to the cross bar, 65 said cross bar being provided with a latch-receiving opening in its body intermediate its ends, and a trouser-supporting clamp removably engaging said opening.
6. A foldable suit hanger comprising a cross bar having a body provided with a recess in its bottom face and depending flanges bordering said recess, said flanges being provided with apertures extending therethrough, a pair of oppositely disposed 70 resilient slides slidably mounted in the cross bar, the inner ends of the slides projecting within the said recess and having offset portions adapted to lockingly engage with said 75 apertures for resiliently holding the slides against movement relatively to the cross bar, said cross bar being provided with a latch-receiving opening in its body intermediate its ends, a trouser supporting clamp including a bent wire loop closed at one end, a latch pivoted to said closed end adapted to be threaded through the said opening for selectively attaching or detaching the loop from the cross bar, and a pair of clamping strips pivotally suspended from the free ends 80 of the loop.
7. A foldable suit hanger comprising a cross bar having a body provided with a recess in its bottom face and depending flanges bordering said recess, said flanges being provided with apertures extending therethrough, a pair of oppositely disposed 85 resilient slides slidably mounted in the cross bar, the inner ends of the slides projecting within the said recess and having offset portions adapted to lockingly engage with said 90 apertures for resiliently holding the slides against movement relatively to the cross bar, said cross bar being provided with a latch-receiving opening in its body intermediate 95 its ends, a trouser supporting clamp including a bent wire loop closed at one end, a latch pivoted to said closed end adapted to be threaded through the said opening for selectively attaching or detaching the loop 100 from the cross bar, a pair of clamping strips pivotally suspended from the free ends of the loop, and a notched flange projecting laterally from each of said strips, the notches receiving the depending limbs of the loop 105 when the strips are swung to a position substantially at right angles to the body of the loop.

In testimony whereof, I sign my name.

HENRY T. HETTINGER.
